WEB SUPPLY MECHANISM

Albert J. Horton, White Plains, N. Y., assignor,
by mesne assignments, to R. Hoe & Co., Inc.,
New York, N. Y., a corporation of New York

Application February 2, 1934, Serial No. 709,497

47 Claims. (Cl. 242—58)

This invention relates to a web supply mechanism for a printing machine and more particularly to a manually operated web replacement mechanism for use in joining the web of a replacement roll to the web of an expiring web roll without interfering with the continuous press operation.

One object of the invention is to provide an improved means for manually moving a web deflecting and cutting mechanism, of the type disclosed in a copending application Serial No. 700,652 into a position which will cause a web pasting and cutting operation to occur.

Another object is to provide a mechanism whereby the web end of the replacement roll may be mechanically clamped to the body of said roll preparatory to making a join and means for releasing the clamp at the time a join is being made.

In regard to the latter object, which is one of the main features of the invention, fingers have been provided which are adapted to be moved into clamped engagement with the web end of the replacement roll and rotate with the web roll when said roll is being accelerated to a speed corresponding to the speed of the running web roll. After such speed is attained and the web on the running web roll has become nearly depleted, an obstruction is moved into the path of the clamping mechanism which will cause a projecting member to engage same and release the said fingers from their clamped engagement with the web at the time a join is being made.

With the above and other objects not specifically referred to in view, the invention consists in certain novel arrangements and combinations 35 which will be fully described in connection with the accompanying drawings and the novel features pointed out in the claims hereunto annexed.

Referring to the drawings:

Figure 1 is a fragmentary end elevational view 40 with a part in section, showing a web supply and web joining mechanism in a web joining and cutting position with one form of web clamp- ing mechanism in a clamp releasing position;

Figure 2 is a view similar to Figure 1, showing a modified form of web clamping mechanism in a clamp releasing position;

Figure 3 is an enlarged end elevational view of the web joining and cutting mechanism in a position preparatory to joining and cutting the web 50 and includes a manual control arm for moving the said mechanism to a web joining and cutting position;

Figure 4 is an elevational view with parts broken away and parts in section of the structure 55 shown in Figure 3;

Figure 5 is a fragmentary detail view of the lower end of the view shown in Figure 4 with a portion broken away to show a mounting for the cutter actuating lever and web clamp actuating abutment for the form of clamp shown in Figure 1;

Figure 6 is an enlarged end elevational view of the web replacement roll mounting and showing the form of web clamping mechanism which corresponds with that shown in Figure 1, in a clamped position on the web replacement roll;

Figure 7 is a side elevational view of the clamping mechanism shown in Figure 6 and also shows a portion of the roll mounting and a contact closing cam in section;

Figure 8 is a plan sectional view taken on the line 8 of Figure 6, showing a means for locking the clamping bar in a set position;

Figure 9 is a plan view of the web clamp, shown in Figure 6, in a clamping position;

Figure 10 is a plan view similar to Figure 9 but showing the clamp in a released position;

Figure 11 is a longitudinal sectional view taken on the line 11 of Figure 9;

Figure 12 is an end sectional view taken on the line 12 of Figure 9;

Figure 13 is a plan sectional view taken on the line 13 of Figure 6, showing a clamping bar mounting;

Figure 14 is a side elevational view of a modified form of web clamping mechanism of the type shown in Figure 2 in a clamped position;

Figure 15 is a plan view of the structure shown in Figure 14;

Figure 16 is an end sectional view taken along the line 16 of Figure 14;

Figure 17 is a side elevational view similar to Figure 14, but showing the clamp in a released position;

Figure 18 is a plan view of the structure with the parts in the position shown in Figure 17;

Figure 19 is an end sectional view taken along the line 19 of Figure 17;

Figure 20 is a diagrammatic view of the web supply and web joining mechanism also includ- 45 ing a wiring diagram of a circuit which is used to control the final web cutting and clamp releasing operation;

Figure 21 is a diagrammatic view similar to Figure 20, showing a modified form of wiring ar- 50 rangement and a treadle member for actuating the web deflecting device; and

Figure 22 shows a modified treadle device with a push button thereon that may be used to operate the web joining mechanism.

45

55

Referring to Figures 1 and 2, the general structure of the web supply mechanism and of the web joining and cutting mechanism includes a web roll supporting reel 25 rotatably mounted on suitable supports 26 and having arms extending therefrom upon which web rolls are supported on short shafts or spindles 27 which engage the core of the roll, in accordance with the general practice. Above the reel 25 is a driven belt 28 which is adapted to engage the periphery of the running web roll to drive same at a speed corresponding with the speed of the printing machine and to accelerate the speed of a web replacement roll to that of the running web, when said replacement roll is moved into contact therewith, before a join is made between the running web end and the web end of the replacement roll. In each of the Figures 1 and 2 the reel 25 is shown with a replacement roll 29 in engagement with the belt drive and an expiring roll 31 in a web joining position, the latter having been moved from the position which is occupied by the replacement roll, by a motor drive or any other suitable driving means (not shown).

A web joining and cutting mechanism is shown as having been moved to a web joining and cutting position, which mechanism comprises a web deflecting frame 32, having a brush 33 mounted thereon, and a cutter frame 34 having a cutter blade 35 mounted at the lower end thereof, each of which frames are pivotally movable preferably about the same axial center. In the mechanism shown, the pivotal mounting for said frames includes a sleeve 36, carried by bearing brackets 37 depending from the machine frame, upon which the cutter frame 34 is mounted. A shaft 38 is carried by the sleeve 36 and the web deflecting frame 32 is fixed to said shaft.

The description of the detail structure regarding the above named mechanism will be found in the aforementioned application, Serial Number 700,652; therefore only such parts as embody features of the present invention will be described in detail in this specification.

It is to be noted that the cutter frame 34 will be maintained in a fixed position, when either in a raised or a lowered position, by means of a pawl 34a which is secured to a shaft 30 that is rotatably supported in the frame 34. The pawl 30 is adapted to engage suitable recesses 37a-37a in the stationary supporting bracket 37, and is biased into engagement with the recesses by a spring 30a. A handle 40 secured to the shaft 30 provides means for releasing the pawl 34a.

After a running web roll 31 has been reduced nearly to exhaustion, the reel is rotated to move the running web W into the path of the web deflecting and cutting mechanism and the web replacement roll is moved into engagement with the belt mechanism 28. The web deflecting and cutting mechanism is then moved from a normally raised position to the operating position shown in Figure 3, and as soon as the running web roll reaches the point of almost complete exhaustion, the said web deflecting and cutting mechanism will be moved to the web joining and cutting position of Figures 1 and 2.

Referring to Figures 3 and 4, a hand actuating lever 39 is shown as freely mounted at the end 70 of the shaft 38 and a clutch collar 41 which operates with said lever, is keyed to the shaft 38. A plunger rod 42 is slidably mounted within a lug 43 projecting from one side of the lever 39 and has a connecting link 44 joining same with a bell crank 45 pivotally mounted at the lower

end of the lever 39. Said plunger rod 42 is maintained in a normally raised position by means of a spring 46, compressed between a collar 47 on the link 44 and a supporting lug 48 on the lever 39, which thereby holds the upper end of the plunger rod 42 against the periphery of the collar 41. Slots 49 are provided in the clutch collar 41 in the path of the plunger rod 42 and are adapted to be engaged by said rod to permit the lever 39 to be clutched thereto. When the plunger rod is in engagement with either of said slots 49, the lever 39 will be maintained in driving engagement with the shaft 38 and will be adapted to move the said shaft to raise or lower the web deflecting frame attached thereto or to move 15 said frame to a web joining position.

The position shown in Figure 3 indicates the pre-joining and pre-cutting position of web deflecting and cutting frames, the frames having previously been moved therefrom from their normal raised position. Before the final web joining and cutting operations are performed, the attendant will release the plunger rod 42 by grasping a handle 51, formed at the lower end of the lever 39, and the free end of the bell crank 45, to thereby rock said bell crank about its pivot, and withdraw the end of the rod 42 from a slot 49. The said lever will then be free to be swung upward until the plunger rod engages another slot 49 which will thus support the lever in a substantially horizontal position (see Figure 20). When in this latter location the lever is in a convenient position to swing the frames forward for a final web joining and cutting operation.

Another rod 52 is slidably mounted in a lug 53, projecting from the lever 39, and in the handle 51, and has a spring 54 compressed between a collar 55 on said rod and the lug 53, which spring forces the rod 52 outward. A stop collar 56 secured to the rod 52, limits the extent of projection of the lower end of the rod 52 beyond the end of the handle 51. A circuit closing switch 57 is secured to the lever 39, above the rod 52, and has a push button 58 projecting below same in the path of the rod 52, which button is adapted 45 to be engaged by the rod 52 when the said rod is pushed inward to close the switch.

A beam 59, which supports the brush 33 and forms a part of the web deflecting frame 32, also has bearings 61 mounted at the bottom thereof, one of which bearings is shown in Figure 4. A shaft 62 is rotatably mounted in said bearings 61 and has a plurality of flapper levers 63 secured thereto and properly positioned to permit operation with full length, half length or three-quarter 55 length web rolls. A second lever 64 is also secured to the shaft 62 and a connecting link 65 is connected to the lever 64 and to a cutter blade releasing lever 67. Said lever 67 is secured to a shaft 68 carried in bearings 69 at the lower end of the cutter frame 34, and is adapted to rock said shaft 68 to actuate a cutter blade releasing latch (not shown). As stated, the web deflecting frame and cutter frame are shown in a pre-joining and pre-cutting position in Figure 3, but will have no 65 effect upon the movement of the running web until the web deflecting frame is moved forward to bring the running web into contact with the replacement roll. Also, when said web deflecting frame is moved forward, the flapper lever will be 70 moved into the path of a web clamp mechanism hereinafter described, which is rotating with the web replacement roll.

It will be observed that both the web deflecting frame 32 and the cutter frame 34 will be moved 75

as one unit from their normal or raised position to the position shown in Figure 3 and will be returned in the same manner by the manual actuation of the hand lever 39. To assist this unison 5 of movement, a rod 72 is joined to the web deflecting frame 32 and is loosely mounted in an opening in the cutter frame 34, a stop collar 73 being secured to the opposite end thereof to provide a limiting stop but to allow sufficient movement 10 between both of said frames to provide means whereby the web deflecting frame may also be moved independently of the cutter frame a limited distance. A spring 74, having one end attached to the web deflecting frame and one end 15 attached to the cutter frame, will hold the two frames in a definite normal relation to each other. Therefore, the web deflecting frame, which is free to move, will be drawn toward the stationary cutter frame 34 by the spring 74, or 20 in other words, will be biased away from the running web and will remain so until it is manually moved to deflect the running web against the replacement roll, when making a web join.

In Figures 1 and 5, an arrangement is shown in 25 which a flapper lever 63a is adjustably secured to a shaft 62a and said shaft is rotatably mounted in bearings 75 on brackets 76, secured to the upper surface of the beam 59. An abutment bar 77 is secured to the brackets 76 and has rubber pads 30 78 fixed thereto, which are adapted to be engaged by the flapper lever 63a. A long connecting link 65a connects a lever 64a secured to the shaft 62a with the cutter blade releasing lever 67 just as in the structure shown in Figure 3.

35 It is to be noted that the structure of the flapper lever 63 and mounting therefor, as shown in Figures 3 and 4 will be actuated by the web clamping mechanism shown in Figures 2 and 14 and the flapper structure shown in Figure 5 will be actuated by the clamping mechanism shown in Figures 1, 6 and 9. In the Figure 5 structure, the flapper lever 63a projects beyond the path of the web and it is therefore made adjustable on the rod 62a to permit operation with web rolls varying 45 in length.

Referring now to the form of clamping mechanism for holding the web end of the web replacement roll against the periphery of the roll as shown in Figure 1 and more clearly in Figures 6 50 to 13; a clamp supporting bar 79, having a scale 80 thereon, is slidably mounted within a split end of a bracket 81 and said bracket is pivotally mounted on pins 82-82, said pins being secured within ears 83, 83 projecting outward from a 55 sleeve 84. Said sleeve is rotatably mounted on a collar 85, one of which is secured to the end of each arm on the reel 25, by means of screws 86. The collar 85 has a shoulder portion 87 which engages an annular recess 88 in the sleeve 84 to hold the sleeve in place. A cam ring 89 is secured to the sleeve 84 and is adapted to actuate a finger 91 to open or close a switch 92 for a purpose to be hereinafter explained. A flat spring 93 is also secured to the outer face of the sleeve 84 65 and bears against the lower inner face of the bracket 81, to exert a pressure against same, whereby the upper or clamp end is normally forced away from the web roll when the clamp is released.

70 The bar 79 is adapted to be clamped within the bracket 81 by means of a lever 94, which is pivotally mounted in walls 95, 95, extending outwardly therefrom. The mounting for said lever 94, comprises a stud having a square central portion 96 which is adapted to fit in a similarly

shaped opening in the lever and has threaded extensions 97, 97 at each side thereof, with threads of opposite hand thereon, as shown in Figure 13. Nuts 98, 98 are fixed within the walls 95, 95 and are engaged by the threaded ends of the stud; 5 therefore, any rotation of the stud will either spread the walls 95 apart or draw them together, which condition will cause the bar 79 to be fixed when in a clamped position or movable when in an unclamped position. 10

A web clamping device is mounted at the upper end of the bar 79 as is clearly shown in Figures 6 and 7, also in the detailed views 9 to 12 inclusive. Said device comprises a bracket 101, which is fixed to the top of the bar 79 by rivets or in any 15 other suitable manner and has a rocker plate 102 pivotally mounted around a shouldered screw 103 on the upper surface thereof. A flat, preferably flexible, plate 104, is secured to a raised edge 105, and, as shown, has two fingers 106, 106 formed 20 thereon, each of which fingers may, if desired, have a friction sleeve 107 of rubber or the like thereon.

A bolt 108 is slidably mounted within a slot 109 extending through one side of the bracket 101 25 and is retained in position by means of a gib 110. Said bolt has a stud screwed therein at 111, which stud has an enlarged head portion 112, passing through a straight slotted opening 113 in the upper surface of the bracket 101 and also through a 30 curved slotted opening 114 in the rocker plate 102. At one end of said curved opening 114, an internal flange 115 is formed, which flange is adapted to engage a circumferential groove 116, when the bolt is pulled out as Figures 7 and 9. It will be 35 observed that when the fingers 106 are in clamped engagement with the web roll, the bolt 108 is in its outward position and the flange 115 is in engagement with the groove 116 in the stud and the entire clamp becomes one rigid unit, but immediately after the bolt is moved inward, the stud is released and moves within the slot 114. The pressure therefore, upon the fingers 106, will be 40 released since the rocker plate will be permitted to move upward over the upper portion of the 45 head 112. Upon further inward movement of the bolt, the rocker plate 102 will be swung outward by the engagement of the stud head 112 with the curved slot 114, to thereby withdraw the fingers 106 beyond the end of the web roll, the parts then 50 being in position, shown in Figure 10. At the instant the pressure on the fingers 106 is released the spring 93 on the bracket 81 will become effective and will swing the bracket 81 about the pivot pins 82 to thereby swing the upper end of 55 the clamping bar 79 outward.

When setting up the above described clamping device the following operations are performed:

After a replacement roll is mounted on the reel 25, the clamping mechanism is arranged to first 60 extend the fingers 106 over the end of the replacement roll, then the clamping bar 79 is forced downward within the bracket 81 to bring the fingers 106 into a tightly clamped engagement with the web end of the replacement roll. The 65 lever 94 is then actuated to rotate the screw threaded ends 97-97 which will clamp the bar 79 within the bracket 81 and thus leave the clamping device in the position shown in Figures 6 and 7. This same operation will be repeated on the 70 opposite end of the web roll, after which an adhesive will be applied to the web end of the replacement roll in any desirable manner.

After the replacement roll has been prepared in this manner, the next operation will be to rotate 75

- the reel and thereby move the replacement roll 29 into driving engagement with the belt drive 28 and the running web into a web joining and web cutting position.
- 5 In order to bring the replacement roll to the proper position in relation to the position of the web joining mechanism, a scale or index is provided on a plate 118, secured to the upper end of the reel support 26, and three pointers 119 are 10 provided on a collar 120, which collar rotates with the reel. With this arrangement, the attendant will move the reel until the pointer reaches the index line which corresponds with the position of the scale 80 on the clamping bar, 15 in relation to the upper edge 81a of the bracket 81. When the readings of the index 118 and the scale 80 correspond, the replacement roll will be in a correct relation to the web joining mechanism.
- 20 The attendant will then bring the web deflecting and web cutting mechanism from a normally raised to the pre-joining and pre-cutting position shown in Figure 3. The hand lever 39 is now returned to a horizontal position as in Figure 20 25 with the rod 42 in engagement with a slot 49, and as soon as the running web roll has reached a point of almost complete exhaustion, the attendant will depress the projecting end of the rod 52 while gripping and pulling downward on 30 the handle 51, and move the rod 52 into contact with the button 58 to close the switch 57. Before the web deflecting frame can be moved to a web joining position by the hand lever 39, however, the adhesive portion on the web end of 35 the replacement roll must be in the correct relation to the brush 33, so that at the time the brush forces the running web against the web roll, the adhesive end of the replacement roll will be approaching the brushes and when it 40 comes directly opposite the brush, the adhesive will adhere to the running web and thereby make a web join.
- To control the position of the web end of the replacement roll in relation to the movement of the brush 33 on the web deflecting frame 32, the said frame 32 is maintained in a stationary position by means of a solenoid actuated latch mechanism, the location of which is indicated at 117, 45 Figure 3, and the detail of which is shown and described in the aforesaid copending application. The arrangement is such that a circuit to the solenoid actuated latch 117 remains broken until both the push button switch 57 and the cam actuated switch 92 are closed. Therefore, after 50 closing the contacts to the switch 57, the cam 89, which rotates with the web clamping device, will close the switch 92 and cause the solenoid 117 to be energized at the time the adhesive portion of the web is in the most desirable position to be 55 acted upon. In Figure 6, the clamping mechanism is shown in a vertical position on the roll and the cam ring is shown as closing the switch 92 which will cause the latch to be released. Upon the release of the latch, the attendant will 60 then be permitted to pull the hand lever 39 downward to swing the web deflecting frame forward against the running web, in time to meet the approaching adhesive portion on the replacement roll, to make a join therewith.
- 70 In moving the web deflecting frame forward, the flapper lever 63a will move directly into the path of the bolt 108 on the clamping device and will be engaged by same during the rotation of the web roll.
- 75 The impact of the bolt against the flapper lever

will cause two things to happen, first the bolt 108 will be driven inward to release the clamping fingers from their engagement with the web end of the replacement web roll and withdraw same beyond the end of the roll, and second, the flapper lever will be rocked around its pivot, the action of which will rock the cutter blade releasing lever 67 when the connecting rod 65a is pulled upward. This will happen immediately after the web join is made and cause the running web to be severed 10 immediately below the join.

Another form of clamping device for clamping the web end of the replacement roll is shown in Figures 2 and 14 to 19 which comprises a bracket 121, secured to the upper end of a clamp supporting bar 79a, within which a bolt 122, having a projecting head 120, is slidably mounted in an opening 123 in the side thereof, said bolt being retained in the opening by means of a gib 124. Two cam portions 125 and 126 are formed in the 20 upper surface of the bolt.

A plate 127 having lugs 128 projecting from the sides thereof, is adapted to slide within grooved walls 129 of a transverse recess 131, provided in the upper surface of the bracket 121. Two pins 25 132 and 133, projecting from the lower surface of the plate 127, are adapted to engage the cam grooves 125 and 126 respectively in the upper surface of the bolt 122.

On the upper surface of the plate 127, a flexible plate 134 is mounted, and has fingers 135 projecting therefrom which are adapted to be brought into clamping engagement with the web roll in a manner similar to that of the previously described clamp. Friction sleeves 136 may be 30 supplied to provide a frictional grip on the web roll.

In operation this form of clamp will be set up in clamped engagement with the web roll in a manner similar to the previously described clamp 40 and the bolt will be set in its innermost position as indicated in Figures 14 and 15.

In Figures 14 to 16 the fingers are shown in a clamped engagement with the web roll. When in this position the bolt 122 is in its innermost 45 location with the head 120 engaging a shoulder 130 on the bracket 121, and the plate 127 is in a slightly inclined position, having been rocked about the lugs 128 as a pivot, by the movement of the outer pin 133 on the raised portion of the 50 cam surface 126. The flexible plate is therefore flexed while in the clamped position but when the bolt is kicked back by the engagement of the flapper lever with the head 120 to release the clamp, plate 127 will return to its normal 55 flat position.

When a web join is to be made with the latter arrangement, the web deflecting frame is moved toward the web replacement roll, which thus moves the flapper lever 63 into the path of the 60 projecting head 120 on the bolt 122, and when they engage, the bolt 122 is moved outward until the flapper lever 63 engages a stop-lug 131, formed at the upper end of the clamp supporting bar 79. As the bolt moves outward, the pin 133 65 will first move downward on the inclined cam surface 126 to release the fingers 135 from contact with the web roll and the pin 132 will move through the curved portion of the cam slot 125 to withdraw the fingers 135 from the path of the 70 roll.

It is obvious from the foregoing description of the clamps that a decided improvement has been made in the method of clamping the web end of a web replacement roll to the body thereof.

Referring now to the electrical diagram, Figure 20 shows a circuit that may be traced from one side of the line marked (L1) through normally open switch 57, conductor 141, latch solenoid 117, conductor 142, to one contact ring 143. Also from the other side of the line marked (L2) to a second contact ring 144. This will bring a source of current to the rings 143, 144 when the switch 57 is closed. The said rings 10 may be mounted in any convenient manner at the axis of the reel 25 and will rotate with said reel. Brushes 140—140, joined to the lines L2 and 142, engage the contact rings 143, 144.

On each arm of the reel 25, a mercury switch 145 is mounted in such position as to close a pair of contacts 139—139 when the replacement roll is in a web joining position and is connected in series with a cam actuated switch 92. The circuit which connects said switches 145 and 92 20 with the current supply, is traced from ring 143, through conductor 146, then through switch 145, line 147, switch 92 and line 148, to the ring 144.

Assuming that the parts are in the position shown in Figure 20 and the attendant has closed 25 the switch 57, while pulling downward on the hand lever 39, the latch releasing solenoid 117 will then be energized as soon as the cam portion on the ring 89 engages the finger 91 to close the switch 92. Immediately upon the release of 30 the solenoid actuated latch 117, the web deflecting brush will be moved inward to thus move the running web against the replacement roll, and when the bolt of the web clamping mechanism engages the flapper mechanism, the web cutting mechanism will be actuated to sever the running web below the join.

In Figure 21 a foot treadle arrangement is shown for moving the web deflecting frame into a web joining position, also a modified form of 40 electrical circuit. The treadle mechanism comprises a treadle 151 pivotally mounted on suitable bearings 152, which is connected to an arm 153, projecting from the web deflecting frame, by means of a connecting link 154. Said arm 45 153 is positioned so as to permit the web deflecting frame to be swung about its axis to a web joining position.

The treadle is so arranged as to permit an attendant to conveniently step on same and at the 50 same time to also permit him to press a push button 155 positioned within reach of said attendant. As shown in Figure 21, one push button 155 is shown on each arm of the reel 25 and each is wired in the electrical circuit in the same 55 manner as the mercury switch 145 of Figure 20. The wiring arrangement from the supply through the latch releasing solenoid 117 and to the contact rings 143 and 144, is the same as that previously described for Figure 21 except that 60 the switch 57 is omitted. The circuit up to the contact rings is now a closed circuit and is completed to actuate the latch solenoid 117, when the switch 92 is closed and the push button 155 is pressed. When the said circuit is completed 65 and the solenoid actuated latch 117 is released, the pressure of the attendant's foot upon the treadle will then become effective to move same downward from the position indicated by the dotted lines to the lowermost position indicated 70 by the full lines and thereby actuate the web joining and cutting mechanism.

It is also possible by means of a foot treadle, to provide an arrangement similar to that shown in Figure 20 by substituting a foot actuated 75 switch closing means for the hand actuated

switch 57. Said arrangement is shown clearly in Figure 22 and comprises a treadle arm 160 pivotally mounted on a support 161, which arm has a connecting link 154a to connect same with the deflecting frame 32 as shown in Figure 21. 5 A switch 162, mounted upon the base of the support, has an actuating lever 163 extending from one side thereof which is adapted to throw the switch from a normally open to a closed position when actuated.

The means for actuating said lever 163 comprises a button 164, slidably mounted within a foot pedal 165, which button rests upon one arm 166 of a bell crank and is normally held in a raised position by the action of a spring 167 attached to another arm 168 of said bell crank. A bar 169 has one end joined to the lower end of the arm 168 and is guided by means of the engagement of a pin 171 within a slot 172 in said bar, which directs the movement of the free end 20 of the bar toward the switch actuating lever 163.

When operating the web deflecting and cutting mechanism with a foot treadle arrangement of the above described type it is only necessary for an attendant to place one foot on the pedal 25 165, which action will close the switch 162 through the movement of the bell crank and bar when the button 164 is forced downward. Having closed the circuit up to the switch 92 (Figure 30 20) in this manner, the complete closure of the circuit is effected when the switch 92 is closed, whereupon the latch 117 is released and the web deflector frame is swung to a web joining position by the continued downward pressure of the attendant's foot upon the treadle. Upon the release of the attendant's foot from the pedal 165, the button 164 and parts cooperating therewith will be returned to their normal position by the action of the spring 167 and the switch actuating arm 163 will be returned by a spring or like 35 means within said switch.

It will be understood that the invention may be embodied in other specific forms without departing from the spirit or essential attributes thereof, and it is therefore desired that the present embodiment be considered in all respects as illustrative and not restrictive, reference being had to be the appended claims rather than to the foregoing description to indicate the scope of the invention.

What I claim is:

1. In a web supply mechanism for a machine operating upon a web drawn from a web roll, a support having a running web roll and a replacement roll thereon, web clamping mechanism maintained in direct clamped engagement with the free end of the web of the replacement roll, and web joining mechanism cooperating with said clamping mechanism to release the clamp when a web join is being made.

2. In a web supply mechanism for a machine operating upon a web drawn from a web roll, a rotatable support having a running web roll and a replacement roll thereon, web clamping mechanism having a portion thereof in direct engagement with the free end of the web of the replacement roll, joining mechanism movable to a web joining position, and means to trip the web clamping mechanism when a web join is being made.

3. In a web supply mechanism for a machine operating upon a web drawn from a web roll, a rotatable support having a running web roll and a replacement roll thereon, means to rotate said replacement roll before making a web join, web 75

- clamping mechanism rotatable with the web replacement roll, a clamping portion thereof adapted to hold the web end of the replacement roll in juxtaposition with the body thereof, web joining mechanism movable to a web joining position, and means actuated by the movement of the web joining mechanism to release the clamped web end.
4. In a web supply mechanism for a machine operating upon a web drawn from a web roll, a rotatable support having a running web roll and a replacement roll thereon, web clamping mechanism having a portion thereof in direct clamping engagement with the free end of the web of the replacement roll, web deflecting and web cutting mechanism movable to a web joining and a web cutting position, and means movable with the web deflecting mechanism to release the web clamping mechanism when a join is being made.
5. A mechanism for holding the free end of the web of a web roll against the body thereof, comprising a movable clamping member having a contact portion adapted to be moved into clamped engagement with the free end of the web, means to lock said movable clamping member in a clamped position, and means adapted to be actuated to release said contact portion independently of the locking means.
6. The combination with a web roll of a mechanism rotatable with the roll, a clamping member projecting therefrom and movable into clamped engagement with the free end of the web of the web roll, means for locking same in a clamped position, and other means to release said clamping member.
7. In a web supply mechanism for a machine operating upon a web drawn from a web roll, a support having a running web roll and a replacement roll mounted thereon, a clamping mechanism rotatable with the replacement roll, a clamping portion on said mechanism adapted to be moved into direct clamped engagement with the free end of the web of the web roll, means to make a join between the web of the running web roll and the replacement roll, and means to release the clamping portion at the time a join is made.
8. In a device for clamping the free end of a web roll to the body thereof, a clamping mechanism movable with the roll and a support for same, said clamping mechanism comprising a movable clamp supporting bar positioned adjacent the end of the roll, a projecting upper portion on said bar extending over the end of the roll and adapted to be moved into direct clamping relation with the free end of the web of the web roll, means for locking same in a clamped position, and means cooperating with said projecting portion to release same from a clamped position.
9. In a device for clamping the free end of the web of a web roll to the body thereof, a clamping mechanism movable with the roll and a support for said mechanism, a bracket carried by said support and having a clamping bar slidably mounted therein, a projecting portion at the upper end of said bar and movable therewith into a direct clamping engagement with the free web end of the web roll, means for locking said bar when the projecting portion is in a clamped position, and means for releasing the projecting clamped portion independently of the locking means.
10. In a device for clamping the free end of the web of a web roll to the body thereof, a clamp-

ing mechanism movable with the roll and a support for same, said mechanism comprising a bracket rotatably mounted on said support and having a clamping bar slidably mounted therein, a projecting portion at the upper end of said bar adapted to engage the free web end of the web roll and hold same intact with the body thereof, and a clamp releasing member to release the projecting portion from engagement with the web end and withdraw same from the path of the web.

11. A device for holding the free web end of a web roll against the body thereof, comprising a clamping mechanism positioned at each end of the web roll, each mechanism including a support rotatably movable with said roll, a clamp member connected with said support and having a movable finger portion which is adapted to engage and press the free end of the web against the body of the roll, and means for releasing the finger pressure and withdrawing same from the path of the roll.

12. A clamping structure for holding the free web end of a web roll intact with the body thereof, comprising a movable finger to frictionally engage the free web end of the web roll, a support for said finger manually movable to move it into a web clamping position, and a slidably member cooperating with said finger to release it from clamped position.

13. A clamping structure for holding the free web end of a web roll intact with the body thereof, comprising a movable member having a finger projecting therefrom and adapted to frictionally engage the free web end of the web roll, a bracket to support said movable member, and a bolt slidably within said bracket and cooperating with said movable member to release the clamping engagement of the finger with the web end and to withdraw same from the path of the roll.

14. A clamping structure for holding the free web end of a web roll intact with the body thereof, comprising a movable plate having a projecting portion in clamped engagement with the free web end of the web roll, a rocker arm to support said plate, a bracket movable with the roll and adapted to support said rocker arm, and a slidably bolt cooperating with said rocker arm, whereby upon movement of the bolt in one direction the clamped engagement of the projecting portion will be released and withdrawn from the path of the web roll.

15. A clamping structure for holding the free web end of a web roll against the body thereof, comprising a yieldable plate having a projecting portion adapted to frictionally engage and press the free web end of a web roll against the body thereof, a slidably member to carry said yieldable plate and a bracket to support said slidably member, a bolt slidably mounted in said bracket, and cam portions on said bolt adapted to be engaged by projections on the slidably member, said clamping structure being manually movable to a web clamping position and the clamping portion thereof being releasable by the movement of the bolt in one direction.

16. A clamping structure for holding the free web end of a web roll intact with the body portion thereof, comprising a bracket movable with the web roll and manually movable to a web clamping position, a bolt slidably mounted within said bracket and having a stud projecting therefrom, a rocker arm pivotally mounted on said bracket and having an arcuate slot therein which is engaged by said stud, and a yieldable plate se-

- 5 cured to said rocker arm having a projecting finger portion adapted to frictionally engage and hold the free web end of the web roll intact with the body portion thereof, and to be released therefrom by the sliding action of the bolt.
- 10 17. A clamping structure for holding the free web end of a web roll intact with the body portion thereof, comprising a bracket movable with the web roll and manually movable to a web clamping position, a bolt slidably mounted within said bracket and having cam portions thereon, a plate slidably mounted within a recess in said bracket and having pins projecting therefrom which engage the cam portions of the bolt, a yieldable member secured to said plate having a projecting finger portion adapted to frictionally engage and hold the free web end of the web roll intact with the body portion thereof, and to be released therefrom by the sliding action of the bolt.
- 15 18. In a web supply mechanism for a machine operating upon a web, a support having a running web roll and replacement roll thereon and movable to bring the replacement roll into a web feeding position, means to accelerate the replacement roll, a manually movable web clamping mechanism positioned at the end of the web replacement roll and rotatable therewith, a projecting finger portion on said clamping mechanism to engage the free end of the web and hold same in
- 20 30 clamped contact with the body of the roll, a slideable bolt cooperating with said projecting finger portion, a web joining mechanism adapted to move the running web into engagement with the peripheral surface of the replacement roll to thereby join same with an adhesive portion thereon, and means movable into the path of the sliding bolt to move same and release the projecting finger portion of the clamp at the time a join is being made.
- 25 19. In a web supply mechanism for a machine operating upon a web, a support having a running web roll and replacement roll thereon and movable to bring the replacement roll into a web supply position, means to accelerate the replacement roll, a manually movable web clamping mechanism positioned at the end of the replacement roll and rotatable therewith, a projecting finger portion on said clamping mechanism to engage the free end of the web and hold same in a
- 30 35 clamped contact with the body of the roll, a slideable bolt cooperating with said projecting finger portion, a web deflecting mechanism manually movable to press the running web against the peripheral surface of the replacement roll to thereby join same with an adhesive portion thereon, a web cutting mechanism, a projecting member movable with said web deflecting mechanism into the path of said bolt, and a link between said projecting member and web cutting mechanism, whereby
- 35 40 upon engagement of the bolt with said projecting member, the finger clamping portion is released and the cutting mechanism is actuated.
- 40 20. In a web supply mechanism for a machine operating upon a web, a support having a running web roll and a replacement roll mounted thereon, a web joining mechanism comprising a pivotally mounted web deflecting frame and a web cutting frame normally positioned in non-operative position and movable simultaneously to a pre-joining position, a hand lever to move said frames, means to limit the movement of the web cutting frame, and a latch means to hold the web deflecting frame fixed to the web cutting frame, a solenoid actuated means to release
- 45 50 55 said latch, an electric circuit to energize said solenoid, a manually actuated switch on the hand lever and a cam actuated switch operable by a rotation of the replacement roll, whereby said electric circuit is closed when both the manually actuated switch and cam switch are closed.
- 55 60 65 70 75 21. In a web supply mechanism for a machine operating upon a web, a support having a running web roll and a replacement roll mounted thereon, a web joining mechanism comprising a pivotally mounted web deflecting frame and a web cutting frame normally positioned in non-operative position and movable simultaneously to a pre-joining position, a hand lever to move said frames, means to limit the movement of the web cutting frame, and a latch means to hold the web deflecting frame fixed to the web cutting frame, a solenoid actuated means to release said latch, an electric circuit to energize said solenoid, a manually actuated switch, a cam actuated switch operable by the rotation of the replacement roll, whereby said electric circuit is closed when both the manually actuated switch and cam switch are closed, which will thereby energize the solenoid and release the web deflecting frame for movement by the hand lever to a web joining position.
- 75 80 85 90 95 22. In a web supply mechanism for a machine operating upon a web, means for moving a running web roll and a replacement roll to a position in which the web of a running web roll can be moved against an adhesive on the periphery of the replacement roll, a manually operated web deflecting means, an electrically operated latch to normally hold said web deflecting means away from the running web, and an electrically operated timing means cooperating with said latch to actuate same and to permit operation of the web deflecting means.
23. In a web supply mechanism for a machine operating upon a web, a support having a running web roll and a replacement roll mounted thereon and movable to bring the web of the running roll into a position for making a web join, a web deflecting mechanism normally biased away from the web of the running roll, means to move said web deflecting mechanism, an electrically actuated latch member to retain the web deflecting mechanism in a fixed position, and means including a timing mechanism to close a latch releasing circuit whereby said web deflecting mechanism is adapted to be released, and manual means to move said web deflecting mechanism to press the web of the running roll against an adhesive portion on the web end of the replacement roll to make a join between same.
24. In a web supply mechanism for a machine operating upon a web, a support having a running web roll and a replacement roll mounted thereon and movable to bring the web of the running roll into a position for making a web join, a web deflecting mechanism normally biased away from the web of the running roll, manually actuated means to move said web deflecting mechanism, an electrically actuated latch to retain the web deflecting mechanism in a fixed position, a manually controlled switch and an intermittently closed timing switch connected in the latch releasing circuit to release the latch and permit the web deflecting mechanism to be moved to press the web of the running roll against an adhesive portion on the web end of the replacement roll to make a join between same.

25. In a web supply mechanism, a rotatable reel having a running web roll and a web replacement roll mounted thereon, a support for said reel, a web joining mechanism, a member 5 rotatable with the replacement roll, a scale on said member to provide a reading relative to the diameter of the roll, a pointer rotatable with the reel and an index cooperating therewith, which 10 reel index and scale are so related that a corresponding reading on both will indicate the correct position for the replacement roll in relation to the web joining mechanism.
26. In a web supply mechanism, a rotatable reel having a running web roll and a web replacement roll mounted thereon, a support for 15 said reel, a web joining mechanism, clamping mechanism for holding the free web end of the replacement roll intact with the body thereof, a scale and indicator cooperating with said clamping mechanism, and an index and indicator 20 cooperating with the reel, said scale and index having corresponding readings whereby upon movement of the reel to a web joining position, the correctness of said position in relation to the web 25 joining mechanism will be determined by the corresponding relation of readings of the scale and index.
27. In a web supply mechanism, a rotatable reel having a running web roll and a replacement 30 web roll mounted thereon, a support for said reel, a web joining mechanism, clamping mechanism for holding the free web end of the replacement web roll in contact with the body thereof, a slideable clamp supporting bar having 35 a scale thereon and an indicating means cooperating therewith, and an index and a second indicating means cooperating with the reel, said scale and second indicating means having similar readings, whereby when the reel is turned to 40 the proper position for making a web join, the readings of both indicating means will agree and constitute an indication of such proper positioning.
28. In a web supply mechanism for a machine 45 operating upon a web, a support having a running web roll and a replacement roll mounted thereon and movable to bring the replacement roll into close proximity with the web of the running web roll, a web joining mechanism normally biased away from the running web, a latch to maintain same in said biased position, electromagnetically operated means to release said latch, a treadle actuated member adapted to move the web joining mechanism to a joining 55 position, a switch in the magnet circuit adapted to be closed when the treadle is engaged by an attendant's foot and a timing means to complete the circuit, whereby the latch is released and the web joining mechanism is actuated by a continued pressure of the attendant's foot upon the treadle.
29. In a web joining mechanism for a printing machine, a web deflecting member adapted to move a running web into web joining engagement with a replacement web roll, manually operated means to operate said web joining mechanism, electrically actuated means to normally hold the web deflecting mechanism away from the running web, an automatically actuated 65 switch, and a manually controlled switch to close a circuit to the electrically actuated means, whereby the web deflecting member is released and the manually operated means becomes effective to make a web join.
- 70 75. 30. In a web joining mechanism for a printing machine, a web deflecting member adapted to move a running web into web joining engagement with a replacement web roll, a treadle to operate said web joining mechanism, electrically actuated means to normally hold the web deflecting mechanism away from the running web, an automatically actuated switch and a manually controlled switch to close a circuit to the electrically actuated means, the manually controlled switch comprising a button on the treadle movable when the treadle is engaged by an attendant's foot, and a mechanism actuated thereby to close said switch, whereby the web deflecting member is released and the treadle becomes effective to make a join.
31. A clamping mechanism for holding the free web end of a web roll against the body thereof, including a clamping member movable axially with respect to the web roll into direct clamping relation with the free end of the web, and means operably associated with said clamping member to release same.
32. A clamping mechanism for holding the free end of a web roll against the body thereof, including a clamping member movable into direct clamping engagement with the free end of the web, and a latch member associated with said clamping member adapted to be tripped to release the clamping member.
33. A mechanism for holding the free web end 30 of a web roll against the body thereof, comprising a clamping member positioned at the end of a web roll, a contact portion projecting over the end of the roll and adapted to be moved into clamping engagement with the free end of the 35 web, and means to release and retract said contact portion from a contacting position.
34. In a clamping mechanism operable with a running web roll, a clamping member arranged to directly engage and clamp the free end of a 40 web against the body portion of a web roll, a clamp releasing member associated with said clamping member, and means movable into the path of the clamp releasing member to release said clamping member.
35. In a web supply mechanism for a machine 45 operating upon a web, a support having a running web roll and a replacement roll thereon, web clamping mechanism having a portion thereof in direct engagement with the free web end 50 of the replacement roll and adapted to hold said end intact with the body of the roll, clamp releasing means, web joining mechanism arranged to move the running web against the replacement roll to make a web join, and means on said 55 web joining mechanism to trip said clamp releasing means and thereby release the free end of the web when a join is made.
36. In a web supply mechanism for a machine operating upon a web, a support having a running web roll and a replacement roll thereon, web clamping mechanism having a portion thereof in direct engagement with the free web end 60 of the replacement roll and adapted to hold said end intact with the body of the roll, clamp releasing means, web joining mechanism arranged to move the running web against the replacement roll to make a web join, a web cutting member, and means on said web joining mechanism to trip said clamp releasing means 65 and to actuate said web cutting member when a web join is made.
37. In a web supply mechanism for a machine operating upon a web, a support having a running web roll and a replacement roll thereon, 70

means to deflect the web of the running web roll against an adhesive portion on the replacement roll, including a pivotally mounted web deflecting member capable of being moved from a non-operative to an operative position, a hand lever freely rotatable on the pivotal axis of the web deflecting member, and means whereby said hand lever is adapted to be clutched to said web deflecting member in any one of a plurality of positions.

38. In a web supply mechanism for a machine operating upon a web, a support having a running web roll and a replacement roll thereon, means to deflect the web of the running web roll against an adhesive portion on the replacement roll to make a web join, including a web deflecting member arranged in a normal pre-joining position, a foot treadle connected with said web deflecting member to move same to a web joining position, releasable latching means to normally maintain said web deflecting member in pre-joining position, and means associated with and operable upon actuation of said foot treadle to release said latching means and thereby permit said foot treadle to move said web deflecting member.

39. In a web supply mechanism for a machine operating upon a web, a support having a running web roll and a replacement roll thereon, means to deflect the web of the running web roll against an adhesive portion on the replacement roll to make a web join, including a web deflecting member arranged in a normal pre-joining position, a hand lever associated with said web deflecting member and adapted to move same, latching means to normally maintain said web deflecting member in a pre-joining position, and manually controlled means cooperating with said hand lever to release said latching means and thereby permit the web deflecting member to be moved to a web joining position.

40. In a web supply mechanism for a machine operating upon a web, a support having a running web roll and a replacement roll thereon, means to deflect the web of the running web roll against an adhesive portion on the replacement roll to make a web join, including a web deflecting member arranged in a normal pre-joining position, a foot treadle associated with said web deflecting member and adapted to move same, latching means to normally maintain said web deflecting member in a pre-joining position, and manually controlled means cooperating with said foot treadle to release said latching means and thereby permit the web deflecting member to be moved to a web joining position.

41. In a web joining mechanism, the combination with means for supporting a running web roll and a replacement roll, means to accelerate the replacement roll to the speed of the running web, a web deflecting member, means to normally bias said web deflecting member away from the running web, means to actuate said web de-

flecting member to make a web join, a latch cooperating with said web deflecting member, and means to actuate said latch before a join is made.

42. In a web supply mechanism for a machine operating upon a web, a support having a running web roll and a replacement roll thereon, a web deflecting member to move the running web against the replacement roll, manually actuated means to move said web deflecting member, a latch member to normally prevent moving said web deflector, and means controlled from said manually actuated means to release said latch.

43. In a web supply mechanism for a machine operating upon a web, a support having a running web roll and a replacement roll thereon, a web deflecting member to move the running web against the replacement roll, manually actuated means to move said web deflecting member, a latch member to normally prevent moving said web deflecting member, an electromagnet to release said latch, and a switch member operable from said manually actuated means to close an electrical circuit and thereby energize said magnet.

44. In a web supply mechanism, a rotatable reel having a web roll and a web replacement roll mounted thereon, a support for the reel, a reel scale on the support, a web joining mechanism, and a member rotatable with the replacement roll having a roll scale thereon to provide a reading relative to the diameter of the roll, and means rotatable with said reel and cooperating with said reel scale, whereby the desired movement of the replacement roll with respect to the web joining mechanism may be determined.

45. In a web supply mechanism for a machine operating upon a web, a support having a running web roll and a replacement roll thereon, web clamping mechanism for clamping the free end of the web of the replacement roll to the body thereof, web joining mechanism including a web deflector and a web cutting member, means to release the web clamping mechanism when the web joining mechanism is moved to make a web join, and means whereby the cutting member is actuated by the clamp releasing means.

46. In a web supply mechanism, a rotatable reel having a web roll thereon, a pointer rotatable with said reel, and a scale having indicia thereon corresponding to various roll diameters mounted on a stationary part and cooperating with said pointer to indicate the amount of reel rotative movement required to locate the periphery of a web roll of known diameter, in a desired position.

47. In a web supply mechanism, a reel having a web roll thereon, said reel being rotatable to dispose said web roll in spaced relation with the web of a web expiring roll, and means to indicate the stop position for said reel to space rolls of different diameters in a desired relation to the aforesaid web.

ALBERT J. HORTON.
